(57) **CLAIM**

The ornamental design for a display screen or portion thereof with graphical user interface, as shown and described.

DESCRIPTION

FIG. 1 is a front view of a first embodiment of the claimed design for a display screen or portion thereof with graphical user interface; and,

FIG. 2 is a front view of a second embodiment of the claimed design for a display screen or portion thereof with graphical user interface.

The uneven-length broken lines are imaginary lines that depict boundaries of the claimed design and form no part thereof. The even-length broken lines showing the rest of the display screen or portion thereof with graphical user interface depict environmental structure and form no part of the claimed design.
